UNITED STATES PATENT OFFICE.

CHRISTIAN H. MARTIN, OF AKRON, OHIO.

ATTACHMENT FOR MUSIC-ROLLS.

1,111,264.

Specification of Letters Patent. Patented Sept. 22, 1914.

Application filed January 18, 1913. Serial No. 742,778.

To all whom it may concern:

Be it known that I, CHRISTIAN H. MARTIN, a citizen of the United States, residing in the city of Akron, county of Summit, and State of Ohio, have invented certain new and useful Improvements in Attachments for Music-Rolls, of which the following is a specification.

My invention relates to a device which is applied to the end of a note-sheet used with player pianos and the like for connecting the sheet to the take-up roller. It is a matter of common experience that the leading end of a note-sheet tears or wears in use and thereby renders the entire roll useless long before the main portion of the note-sheet begins to show wear.

My aim is to provide means which may be attached initially to a new note-sheet roll, or which may be applied by the user to an old roll, for effectively transmitting the tension from the take-up roller in such a way as to cause a smooth travel of the note-sheet across the tracker-bar, obviating any tendency to tear the V-shaped leading end of the sheet.

My invention also provides means whereby the same device used for securing the leading end of the sheet to the take-up roller serves to maintain the note-sheet in rolled condition when it is not in use, thus doing away with the use of separate rubber bands now commonly employed for this purpose.

In the accompanying drawings which form a part of this specification, Figure 1 is a front elevation of a portion of the mechanism of a player-piano or the like, showing the note-sheet and the take-up roller, the note-sheet being provided with my improved device; Fig. 2 is a diagrammatic view showing my device about to be applied to a note-sheet; Fig. 3 is a transverse sectional view of the take-up roller and associated parts; Fig. 4 is a transverse sectional view similar to Fig. 3, but showing a different mode of connection between the note-sheet and the roller; Fig. 5 is a transverse sectional view of a note-sheet rolled and maintained in that condition by the same means which is used for attaching its leading end to the take-up roller.

Referring to the drawings in detail, the numeral 1 designates a note-sheet mounted upon its roller 2 journaled in bearings in the frame 3 of a player-piano. The note-sheet has been unwound sufficiently from its roller

to permit its leading, V-shaped end to be drawn across the face of the tracker-bar 4 and secured to the take-up roller 5. The means of attachment include a rubber band 6 provided at one end with a ring 7 and a spring fastener 8 for engagement interchangeably either with the hook 9 of the type of take-up roller shown in Fig. 4, or the spring eye 10 with which the roller of Fig. 3 is equipped. The other extremity of the rubber band is secured by means of a spring eye 11 to a device composed in part of a plurality of strips 12 of strong flexible fabric, which are glued to the note-sheet. This system of strips is associated with a pair of triangular pieces 13 and 14 adapted to be applied to opposite sides of the V-shaped end of the note-sheet. A strip 15 having in general a rectangular outline is folded along the line 16 and carries the triangular pieces. The narrow strips 12 diverge from the juncture of the two triangular pieces and extend for a considerable distance along the top or outer surface of the note sheet, as shown clearly in Fig. 1, thus transmitting tension from the rubber leader 6 to the note-sheet evenly across the entire width.

The leader 6 may have its end split to engage the outer surfaces of the two triangular members 13 and 14, as shown at 17 and 18, the eye 11 passing through all the thicknesses of material and clenching the same firmly in conjunction with the adhesive substance with which they are applied to the note-sheet.

It will be apparent that I may furnish the device with the surfaces gummied so that it will be applied by the user to note-sheets now in use, the provision of the two attaching means, namely, the ring and the spring fastener, adapting it for use both with the take-up rollers now in extensive service and with my improved take-up roller shown in detail in Fig. 3. By distributing the tension to the note-sheet at a point where it has reached its maximum width, I avoid any strains in the sheet tending to tear the same near its reduced V-shaped end, and the outer strips 12 in conjunction with the triangular members 13 and 14 afford an efficient guard against tearing or undue wear of the note-sheet from handling. The use of the elastic leader 6 makes it possible to keep the note-sheet in smoothly rolled condition by forcing the spring clasp into the eye 11, as shown

in Fig. 5. The note-sheet and its attachments thus form a unit which is self-contained and not liable to become unrolled.

While I have illustrated and described only one preferred embodiment of my device, I realize that it is susceptible of wide variation, and I do not desire to be limited to the precise structure depicted herein.

Having thus described my invention, I claim:

1. Attaching means for music rolls, comprising a body portion adapted to be attached to an end of a roll, a plurality of strips extending therefrom across the face of the roll to a point at which said roll has reached its normal width, and a pair of strips alined with margins of said roll and reinforcing the same.

2. Attaching means for music rolls comprising a body portion adapted to be attached to an end of a roll, and means for evenly distributing tension across the face of the roll consisting of a plurality of reinforcing strips extending from said body portion to a point at which said roll has reached its normal width and diverging across the face of the roll, and a pair of similarly extending strips alined with margins of the roll.

3. Attaching means for music rolls comprising a body portion adapted to be at-

tached to an end of a roll, a plurality of strips adapted to extend across the face of the roll to a line at which the roll is of substantially full width, and a pair of strips 35 adapted to be alined with margins of said roll and to reinforce the same to said line, said body portion having secured thereto an elastic member of sufficient length to permit it to be wrapped around said roll and provided with fastening means adapted both to engage with means on said body portion to hold the roll when in wrapped condition and to engage with a take-up roller when the roll is to be unwrapped. 40 45

4. Attaching means for music rolls comprising a body portion adapted to be attached to an end of a roll, an elastic member secured thereto and adapted to engage with a take-up roller and by its elasticity to relieve the initial strain upon the roll, and means for evenly distributing the tension transmitted thereby across the face of the roll consisting of a plurality of reinforcing strips extending from said body portion 50 55 divergently across the face of the roll, and a pair of similarly extending strips alined with margins of the roll.

CHRISTIAN H. MARTIN.
